FILLING NOZZLE

James D. Elsom, Evanston, Ill., assignor of twenty-four percent to Lawrence E. Gould, and twenty-four percent to Frank J. O'Brien, both of Chicago, Ill.

Application September 4, 1937, Serial No. 162,467

7 Claims. (Cl. 226—127)

My invention relates to filling nozzles and particularly to means applied thereto, acting to automatically interrupt the flow of liquid being delivered through the nozzle when the liquid in a container shall rise to a predetermined level.

In the filling of tanks with liquid fuel, it is desirable that means should be provided that will act automatically to interrupt the delivery of liquid when the tank is filled to a level near the point of overflow. A number of devices have been suggested for the purpose, but the operation of none thereof has been entirely satisfactory, certain inherent shortcomings being present that are overcome in the design herein illustrated.

An object of my invention is to provide mechanism that will operate with certainty but will not operate to close the shut-off valve if drops of liquid, that may occur from splashing within the tank, shall enter the port located at the limit point. My device is so designed that a small amount of liquid entering the port will not interrupt the flow of liquid through the nozzle.

In general, my device includes a motor of some sort applied to the filling nozzle, the motor serving to operate a piston, acting in a cylinder having a restricted outlet, the piston acting to compress air during normal operation. A port is provided at the high level limit through which liquid may be admitted to the cylinder and as liquid is practically incompressible, the motor will be slowed down when the level of liquid reaches the port. The shut-off valve provided in the nozzle is maintained in open position by the exhaust pressure from the motor built up by reason of a restricted outlet therefor, and when the speed of the motor is substantially reduced, the volume of exhaust air becomes less and consequently the pressure is reduced. This permits a spring to close the valve and stop the flow of liquid through the nozzle. In addition, means are provided, operated by the valve for sounding an alarm.

The invention will be more readily understood by reference to the accompanying drawings, in which;

Fig. 1 is a plan view of a nozzle to which my improvement has been applied;

Fig. 2 is a side elevation thereof;

Fig. 3 is a longitudinal sectional view;

Fig. 4 is an end view of a motor such as I prefer to use;

Fig. 5 is a top plan view; and,

Figs. 6 and 7 are enlarged sectional views on the lines 6—6, 7—7 of Fig. 4.

The nozzle, as best shown in Figs. 1 to 3, com-

prises a delivery end 10, a body portion 11 and a hose connecting end 12. Mounted within the body of the nozzle is a valve 13 held in closed position by a spring 14 and engaging a bellows 15 at its lower end. A shell 16 encloses the bellows, the shell having a bleeder port 17. Air admitted through the pipe 18 acts on the bellows, tending to compress the same and to open the valve, the pipe 18 being connected to the exhaust passage 19 in the motor body.

The motor, indicated generally by the numeral 20, is supplied with air under pressure through a pipe 21 delivered by a hose 22. Within the motor body is mounted a piston 23, a reversing valve 24 and a hand operated shut-off valve 25.

The air motor is of a conventional type, the operation of which is as follows:

Air admitted through the pipe 21 is delivered to the passage 21a, Fig. 7, thence to the hand operated valve 25 through which the air is conducted to a passage 31; from this point the air is delivered to the reversing valve 24. When the reversing valve is in the position shown in Fig. 6, the air from passage 31 enters cross-over space 33 and thence through passageway 34 into the right hand end of the cylinder for the piston 23. This causes the piston to move to the left. At this time, due to the reversal of position of the valve 24, the passageway 35 leading from the left hand end of the cylinder is connected to the exhaust port 36 through the cross-over space 37 in the valve 24, the port 36 opening into the atmosphere. When the air enters the right hand end of the cylinder as above described, it causes the piston 23 to move to the left, as shown in dotted lines in Fig. 6. In doing this the air supplied through the passage 31—in the position of Fig. 6, then travels through passageway 32 to the cross-over 38 in the piston and thence through the passageway 39 to the right hand end of the reversing valve 24 thereby shifting it to the left. When in this position the air is delivered to the left hand end of the piston and the air in the right hand end of the cylinder is discharged through passage 40, thence through cross-over 41 in the reversing valve and thence to the exhaust passage 42, and to the pipe 18 connected to the space surrounding the bellows.

As a warning device that the valve is closed and the flow of liquid stopped, I provide a whistle indicated at 43 in Fig. 3, which is operated as follows:

Mounted adjacent to the shut-off valve 13 is a bracket carrying a lever arm 44, one end of which overlies the valve and the other end un-

derlies the plunger 35. The upper end of the plunger contacts the stem of a valve 46 controlling the passage of air from a passage 41, in communication with the intake passage 21a, to a passage 48 that leads to a tube 49 through which the air is delivered to the whistle. Of course, when the hand valve 25 is shifted, the whistle passage is closed. The reciprocating piston 23 of the motor has a piston rod 26 connected thereto, the rod passing through a gland into the discharge end of the nozzle and terminating in a piston 27. The piston operates in a cylinder 28, having a small outlet or discharge port 29, thus forming an air compressor in which air is compressed within the cylinder and discharged through the restricted outlet. The inlet ports for the air are indicated at 30, these being located at the level to which it is desired to fill the tank or other container.

20 The arrangement is such that when the compressor is operated on air, the motor will reciprocate freely and the exhaust therefrom, which is directed through the pipe 18, will act on the bellows 15 to maintain the valve in open position; this for the reason that the air cannot escape through the bleeder port 17 fast enough to avoid building up of pressure. When, however, liquid in any substantial quantity enters the ports 30 into the cylinder 28, the speed of the motor will be very greatly reduced due to the difficulty in ejecting liquid through the restricted outlet 29 from the cylinder. Consequently the volume of exhaust air will be proportionately reduced and sufficient thereof can escape to reduce the pressure to a point that will enable the spring 14 to close the shut-off valve.

25 It will be noted that in the event a small amount of liquid enters the compressor, as by splashing, it may momentarily slow down the motor, but inasmuch as the liquid will be immediately expelled, the normal operation will be resumed. However, if liquid continuously enters the air inlet ports to the compressor it cannot be expelled quickly and the motor speed will be greatly reduced.

30 It should be understood that the apparatus shown is illustrated only and may be varied as to substantially all of the instrumentalities without departure from the inventive idea. Therefore, the scope of the invention should be determined from the appended claims.

I claim:

1. In combination, a filling nozzle having a shut-off valve, a motor carried by said nozzle, an air compressor operated by the motor, means providing a liquid inlet to the compressor, said inlet being located at a point on the nozzle representing a filling limit, and means operated as a result of a reduction of speed of the motor following admission of liquid to the compressor for closing said valve.
2. In combination, a filling nozzle having a shut-off valve, an air compressor and means for operating the same, means providing a liquid inlet to the compressor, said inlet being located

at the filling limit of the nozzle, and means operated by a reduction of speed of the compressor-operating means, following admission of liquid to the compressor for closing said valve.

3. In means for automatically interrupting the flow of liquid through a nozzle, the combination with the nozzle body of a cylinder and piston adapted to compress air and to discharge the same through a restricted opening, said nozzle body having a part located at a predetermined shut-off level and acting as a liquid inlet to said cylinder when the level of liquid rises to said part, a motor for reciprocating said piston, a shut-off valve in said nozzle, and means operated by a reduction of speed of said motor following the entrance of liquid into said cylinder for actuating said valve to interrupt the flow of liquid through the nozzle.

4. In a device of the class described, the combination of a nozzle body having a shut-off valve, a reciprocating motor mounted on said body, an air compressor operated by said motor and having an air inlet, the compressed air from which is discharged through a restricted outlet, the air inlet to said compressor being located at a point representing the filling limit of the nozzle, and means controlled by a reduction of the normal speed of said motor for effecting the closing of said valve.

5. In combination, a filling nozzle, a motor mounted thereon, a cylinder and piston located at a point near the discharge end of the nozzle, said piston being reciprocated by said motor to compress air in said cylinder, means providing an inlet opening to said cylinder at a point representing the filling limit, whereby the entrance of liquid into said cylinder effects a speed reduction of the motor, a shut-off valve in the nozzle and means operated as the result of the reduction of speed of the motor for closing said valve.

6. In combination, a nozzle, an air motor mounted thereon, an air compressor operated by said motor and located near the discharge end of the nozzle, means providing an inlet opening to the compressor at a point near the discharge end of the nozzle, a shut-off valve and means subject to the pressure of the exhaust air from said air motor for controlling said valve whereby upon a reduction of speed of said motor, due to the entrance of liquid into the compressor, said valve is closed.

7. In combination, a nozzle having a motor thereon, an air compressor operated by said motor and located at a point near the discharge end of the nozzle and having an air inlet, the air inlet to the compressor being located at a point representing the filling limit of the nozzle, a shut-off valve in the nozzle, a bellows connected to the valve and means operated by a reduction of speed of said motor for varying the air pressure on said bellows to effect the closing of said valve following the admission of liquid into said compressor.
